UNITED STATES PATENT OFFICE

2,539,560

FOOTBALL POSITION INDICATOR

Jeff E. Wilson, The Dalles, Oreg.

Application January 30, 1948, Serial No. 5,317

4 Claims. (Cl. 33—46)

1

This invention relates to apparatus for determining and visibly indicating the exact position of a football on the playing field during a game, to the players, the officials and the spectators.

The primary object of the invention being to provide apparatus of this nature which is accurate and easy to operate, simple and serviceable in construction, and relatively inexpensive to install, and which will eliminate errors in determining positions of the football resulting from play and those resulting from actions of the officials, such as the placing of the football in carrying out penalties and in returning the football to the original line of scrimmage after an incomplete or illegal play.

Another important object of the invention is to provide a football field linesman's device of the above indicated character having a telescope for accurately sighting upon the football on the playing field which is supported for movement along the side of the playing field and which includes pointer means arranged indicatively relative to stationary linear yard indicating means positioned with reference to the yard markings on the playing field, whereby by sighting the telescope on the football before the commencement of a play and again at the end of a play, the exact distance, if any, that the football has been moved is visually exhibited, and at the same time the additional yardage required to be made by the offensive team within the remaining number of "downs" for attaining a "first down" is visually exhibited.

Another important object of the invention is the provision of a device of the character indicated above, in which the sighting telescope and pointer means can be suspended from an overhead cable or track, or movably mounted upon ground level rails, positioned along the sidelines of the playing field, and provided with means for holding the same in a selected position whereby accidental shifting, involving inaccurate exhibition, is eliminated.

Other important objects and advantages of the invention will be apparent from the following description and accompanying drawings, wherein for present purposes of illustration only, specific embodiment of the invention are set forth in detail.

In the drawing:

Figure 1 is a front elevation showing one embodiment of the present invention, involving suspension of the ball position and yardage indicating means from an overhead cable and showing the device in use by an official.

2

Figure 2 is a top plan view of Figure 1.

Figure 3 is a front elevation of another embodiment of the invention, involving support of the indicating means on ground rails.

5. Figure 4 is a left-hand end elevation of Figure 3 on an enlarged scale.

Figure 5 is a transverse vertical section, taken on the line 5—5 of Figure 3.

10. Figure 6 is an enlarged fragmentary sectional and elevational detail of the telescope sighting means.

Referring in detail to the drawings, and first to Figures 1 and 2 thereof, the device therein shown comprises a cable or rod 7 supported parallel to the ground 8 by suitable means, such as posts 9, placed parallel with and at a suitable distance, for instance 12 feet, from a side line of the football playing field. Suspended from the cable 7 for movement therealong is the frame, generally 10, designated 10, comprising vertical end members 11, 11 connected adjacent their upper ends by a horizontal longitudinal member 12, strengthened by diagonal braces 13, 13 extending downwardly to the end members. At a point slightly below the mid-height of the frame 10 a longitudinal horizontal slide bar or track 14 is affixed at its ends to the end members 11, 11. A telescope ball sighting device 15, which may be in the general form of a surveyor's transit, is slidably mounted for movement along the slide bar or track 14, and has depending from the base 16 thereof the downwardly tapering pointer 17, on whose lower end is rotatably mounted on a vertical axis the "down" indicator 18, in the form of a cube having a numeral 19 on each vertical face thereof corresponding to one of the four "downs" of football play.

Rotatably reversibly supported between the end members 11, 12 below the track 14 by trunnions 20', 20' on sleeves 20, 20 slidably embracing the end members having set screws 23, 23 for locking the sleeves at selected elevations on the end members, is the horizontal yardage scale 24, which is longitudinally divided by fractional yard marks 25, each set of which is designated by a corresponding numeral 26 in consecutive order, from one end of the scale toward the other. The yard marks 25 run in the opposite direction on the opposite side of the scale 24. The "downs" indicator 18 is positioned beneath the scale 24. Similar but reversed scale markings are on the opposite side of the scale 24.

On each end member 11 is mounted a friction brake 27 pivoted at 28 to engage the corresponding one of the pulley wheels 29, 29 mounted in

forks 30, 30 on the upper ends of the end members and riding on the cable 7, which support the frame 10 on the cable. Operating rods 31, 31 are pivoted to the brakes and depend alongside of the end members through guides 32, 32 which act as stops for one end of helical expanding springs 33, 33 which press upwardly against stop flanges 34, 34 on the rods, thereby normally yieldably applying the brakes to prevent undesired or accidental movement of the frame 10 along the cable 7. Handles 35, 35 pivoted below the guides 32, 32 on the end members 11, 11 and connected to the lower ends of the operating rods enable momentarily releasing the brakes when desired to permit shifting the frame 10 along the cable, as in moving the device to follow play and progress of the football on the playing field.

The telescopic sighting device 15, being preferably of conventional form has its telescope element 35' set at right angles to the playing field sideline, but can be elevated and declined to follow and sight upon the football in accordance with the distance of the ball from the sideline, as will be understood. In using the above described device, the frame 10 is moved along the cable 7 to the area of play and the ball is sighted at the beginning of a series of "down" by moving the sighting assembly 15 along the frame track 14 until the ball is centered in the telescope 35'. In this position the pointer 17 indicates on the scale 24 the exact position of the ball. On the next play the ball is again similarly sighted, and the "downs" indicator 18 having been rotated to exhibit the next consecutive numeral 19, the pointer 17 will show on the scale 24 the exact yardage made on the play, if any, and the "down." The device is left in the position of the prior "down" or play until the succeeding play has been run off, so that should any dispute arise as to the starting point of such succeeding play, the device will exactly and reliably show the correct starting point, such as in the event the football is called back on an incomplete play or for the purpose of stepping off penalty yardage.

Referring now to the embodiment of the invention shown in Figures 3 through 6, this has in common with the above described embodiment, a frame 10a which includes the track 14a for the sighting assembly 15a with its depending pointer 17a, terminating in the "downs" indicator 18a and the horizontal longitudinal scale 24a traversed by the pointer 17a. Instead of the frame being suspended from a cable, the frame and members 11a, 11a are in the form of forks, as shown in Figures 4 and 5, composed of front and rear legs 36, 37, respectively, braced intermediate their ends by cross members 38, and the legs have journaled between their lower ends the axles 39 having flanged wheels 40, 40 thereon which run on rails 41, 41 on a base 42 staked or otherwise anchored to the ground 8, as indicated at 43.

The yardage scale 23a is mounted on and between the cross members 38, 38 of the two end members 11a, 11a by trunnions 44, 44 journaled therethrough and provided with turning handle wheels 45, 45 whereby the scale can be turned. The scale markings on opposite sides of the scale are reversed, as is the case with the first described embodiment, so that when play is reversed on the field the scale 24a is reversed so that the scale markings will run in the proper direction.

As shown in Figure 6, the base 16 of the telescopic sighting device 15a may have a socket 46 in which is rotatably confined a head 47 on the upper end of the pointer 17a, so that instead of having the "downs" indicator 18a rotate on the lower end of the pointer, the pointer itself is rotatable to change the indicating position of the "downs" indicator 18a.

What is claimed is:

1. A football field linesman's device comprising a frame adapted to be positioned along the sideline of a football field, means supporting said frame for longitudinal movement parallel to the sideline, said frame comprising a horizontal track, a horizontal yardage scale spaced below said track, a football sighting means mounted for movement along said track, and a pointer depending from said sighting means and traversing said yardage scale, said yardage scale having longitudinally arranged yard marks on opposite sides of said scale running in opposite directions, and means mounting said yardage scale on said frame for rotation on a longitudinal axis of said scale whereby said scale can be rotated to show the side thereof corresponding to the direction of play on the football field.

2. A football linesman's device comprising a frame having vertical end members, a horizontal track secured to and between said end members at a level substantially vertically spaced from the lower ends of said end members, support means supporting said frame for movement along and parallel to a sideline of a football field with the lower ends of said end members in relatively closely spaced relation to the ground, a horizontal yardage scale secured to and between the lower ends of said frame end members below said track, and a football sighting and position indicating assembly comprising a sighting device mounted on said track for movement therealong, and a pointer depending from said sighting device and traversing said yardage scale.

3. A football linesman's device comprising a frame having vertical end members, a horizontal track secured to and between said end members at a level substantially vertically spaced from the lower ends of said end members, support means supporting said frame for movement along and parallel to a sideline of a football field with the lower ends of said end members in relatively closely spaced relation to the ground, a horizontal yardage scale secured to and between the lower ends of said frame end members below said track, and a football sighting and position indicating assembly comprising a sighting device mounted on said track for movement therealong, and a pointer depending from said sighting device and traversing said yardage scale, said sighting device comprising a telescope base and a telescope pivoted on and extending across said base for swinging in a vertical plane.

4. A football linesman's device comprising a frame having vertical end members, a horizontal track secured to and between said end members at a level substantially vertically spaced from the lower ends of said end members, support means supporting said frame for movement along and parallel to a sideline of a football field with the lower ends of said end members in relatively closely spaced relation to the ground, a horizontal yardage scale secured to and between the lower ends of said frame end members below said track, and a football sighting and position indicating assembly comprising a sighting device mounted on said track for movement therealong, and a

pointer depending from said sighting device and traversing said yardage scale, said pointer being pivoted to said sighting device to rotate on a vertical axis relative to said sighting device.
